ALARM SYSTEM

James O. Howton, Freewater, Oreg., assignor to
Howton Radio Alarm Company, Seattle, Wash.

Application June 7, 1938, Serial No. 212,380

13 Claims. (Cl. 177—314)

This invention relates to alarm systems, and has as an object to provide in conjunction with such a system, means designed to insure that the system is properly conditioned by a person authorized to close the protected premises, as at night, and to open them, as in the morning.

In order that the invention may be fully understood, I have shown two practical embodiments thereof, by way of example, in the accompanying drawings with reference to which explanation of the invention will be made.

In the drawings:

Figure 1 shows diagrammatically one embodiment of the invention in proper night condition.

Figure 2 shows the embodiment of Figure 1 in proper day condition.

Figure 3 shows diagrammatically a second embodiment of the invention in proper night condition, and

Figure 4 shows the embodiment of Figure 3 in proper day condition.

For the purpose of illustration the basic alarm system is assumed to be a radio alarm system such as is disclosed, for example, in my pending applications Serial No. 184,713, filed January 12, 1938, and Serial No. 191,788, filed February 21, 1938.

Referring first to Figures 1 and 2, reference numeral 10 designates generally a radio transmitter, such as is disclosed in the above mentioned applications, including an aerial 11 and a ground 12. Operation of the alarm apparatus is initiated by means of a relay whose coil is indicated at 13, and it is here assumed that an alarm will be broadcast when the relay coil, for any reason, becomes deenergized. One end of coil 13 is connected by a wire 14 with the positive side of a battery 15 which may be the storage battery as provided for the alarm message producing apparatus according to the above applications. The other end of coil 13 is in connection with an alarm or protective circuit 16, here assumed to be a burglar circuit, which, through window switches indicated at 17 and a door switch indicated at 18, is led to one end of the coil 19 of a relay A. The other end of coil 19 is in connection with the negative side of battery 15 through a wire 20. It will be understood that any appropriate number and arrangement of switches may be made within the protected premises, a wall of the latter being designated at 21 and a door at 22, this door being assumed to be the one designated for use by an authorized person closing or opening the enclosed premises. It will be evident that with switches 17

and 18 closed, as shown in Figure 1, both of coils 13 and 19 are energized, and, in view of the energization of coil 13, the alarm message producing means, as above mentioned, is maintained inoperative.

Arranged in door 22, as shown at the right, Figures 1 and 2, is a lock comprising a movable bolt 23, here shown as longitudinally reciprocable, adapted to be projected into a suitable recess in the adjacent wall or jamb 21 to lock the door, as shown in Figure 1. Bolt 23 is reciprocable by means of a rotary key-controlled operator 24, and is guided in any suitable manner. The bolt is provided on its upper side with a square notch 25.

Above bolt 23 is mounted a disc 26 of insulating material on a rotary key-controlled operator 27. Disc 26 has projecting fingers 28 and 29, and is provided in its lower portion with a cam slot 30 in which is engaged a pin 31 fixed on a vertically reciprocable detent member 32 which is suitably guided as by a bracket 33. With bolt 23 in unlocking position, as shown in Figure 2, notch 25 is to the right of the lower end of detent member 32. When the bolt 23 is in locking position, as in Figure 1, the detent is in register with notch 25 and may be projected into the latter upon counterclockwise rotation of its direct operator 27.

Disc 26 is provided with a square peripheral notch 34 which is engageable by a reciprocable and suitably guided spring-urged latch member 35 when the disc is in the daytime position of Figure 2. Latch 35 is in suitable pivotal connection with an armature 36 which is associated with a coil 37.

The negative side of battery 15 is in connection through a wire 38 with the arm 39 of a switch 40, the arm being normally spring-biased to closed position but being engageable by a pad of insulation 41 on the inner end of bolt 23 when the latter is moved to unlocking position so that switch 40 is opened and held open as shown in Figure 2. The positive side of battery 15 is connected by a wire 42 with one terminal of a buzzer or other suitable signalling device 43, the other terminal of the latter being led to the fixed point of a switch 44 which includes an arm 45 normally spring-biased to switch closing position. Arm 45 is engageable by finger 29 of disc 26 to open switch 44 when the disc is rotated from the position of Figure 2 to the position of Figure 1. A further switch 46, similar to switch 44, includes an arm 47 engageable by finger 28 to open the switch when the disc 26 is rotated

from the position of Figure 2 to that of Figure 1. The switch arm 47 is connected by a wire 48 with wire 16 at the point 49 and the fixed contact of switch 46 is connected by a wire 59 with wire 29 at the point 51. Interposed in wire 59 is an adjustable resistance 52.

Relay A includes a fixed contact 53 connected to wire 33 and cooperable with an arm or contactor 54 which is in connection with one end of coil 37 through a wire 55. The other end of coil 37 is in connection with wire 42 through a wire 55'. Relay A includes a second arm or contactor 56 movable in unison with arm 54 and cooperable with fixed contacts 57 and 58, arm 56 being in connection with wire 33. Contact 58 is in connection with a red lamp 59 and a wire 60 runs from the latter to wire 42. Wire 60 is also in connection with one side of a green lamp 61 whose other side is in connection with contact 57. Arms 54 and 56 are normally spring-biased to the position shown in Figure 2 so that contact is broken at points 53 and 57 and made at point 58.

With the system in the condition shown in Figure 2, coil 37 is deenergized due to the break at point 53 of relay A, and consequently latch 35 is engaged in recess 34 so as to lock disc 26 against movement. Red light 59 shows due to the circuit established through point 53 of relay A. When the authorized person leaves through door 22 and closes the same, switch 18 will be closed and if the alarm circuit 16 is intact, current will flow through coil 19 of relay A so that arms 54 and 56 are drawn to the position of Figure 1 into engagement with contacts 53 and 57. As a result, red light 59 will be extinguished and green light 61 will show. These lights are conveniently placed so that the operator may be advised of the condition of the alarm circuit by reason of the illumination of one or the other, the two being distinguishable by their different color. A circuit is completed through contact 53 to coil 37 so that latch 35 is retracted from notch 34 and frees disc 26 for rotation. Switch 46 remains closed so that a shorting circuit for the alarm circuit is maintained through wires 48 and 59. This shorting circuit is balanced with the alarm circuit by means of resistance 52 so that in the daytime condition of the system the alarm circuit may be tested, as required.

With door 22 closed, the person leaving the premises locks the door so that bolt 23 takes the position of Figure 1, and switch 49 is closed. Disc 26 is still in the position of Figure 2 and since switch 44 remains closed, a signal is sounded by the buzzer 43, giving a reminder that a further step has to be taken. Accordingly, by means of a key, preferably a different one from that required by operator 24, the person closing the premises turns disc 26 in a counter-clockwise direction. Turning of the disc, however, will be impossible if the alarm circuit is not in operative condition since in that case coil 37 will be deenergized and latch 35 will be engaged in notch 34. On the other hand, if bolt 23 has not been locked, disc 26 cannot be turned since the lower end of detent member 32 will immediately abut the top surface of bolt 23 to the left of notch 25. Assuming, however, that bolt 23 is in the position of Figure 1 and that the alarm circuit is intact, disc 26 is freely rotatable by the key to cause detent member 32 to be engaged in notch 25 of bolt 23, to open switch 44 due to engagement of finger 28 with

arm 45, and to open switch 46 due to the engagement of finger 28 with arm 47. Bolt 23 is thus held in locking position and the buzzer and shorting circuits are broken. If the alarm circuit is now disturbed by breaking it at any point, relay coil 43 will be deenergized and an appropriate message will be broadcast.

When the premises are to be opened, disc 26 is first turned in a clockwise direction, and latch 35 cannot prevent this operation even though the alarm circuit has been disturbed and coil 37 deenergized since in that case latch 35 will merely ride on the full periphery of disc 26 until notch 34 is reached. When disc 26 has been turned to the position of Figure 2, the shorting circuit for the alarm circuit will have been completed due to the closing of switch 46, and due to the closing of switch 44, buzzer 43 will give a signal. Detent member 32 will have been lifted clear of notch 25 so that upon moving bolt 23 to the unlocking position of Figure 2 door 22 is free to be opened and the buzzer circuit is broken at switch 43.

In the embodiment of the invention just described the control mechanism for the bolt and the mechanism controlled by and controlling operator disc 6 have a fixed locational arrangement, being all located in the door. In the embodiment of Figures 3 and 4, only the bolt and its operator are positioned in the door and the co-acting instrumentalities are all positioned in the adjacent jamb so that the wiring problem is somewhat simplified inasmuch as it is unnecessary to carry the circuits to a movable part. Simplification in the latter respect, it is pointed out, may also be achieved by mounting the bolt and associated instrumentalities in the jamb, reversing the disposition shown in Figures 1 and 2.

Referring to Figures 3 and 4, bolt 23a has adjacent its outer end a notch 25a, and is key-controlled as before. The door is designated at 22a and the adjacent jamb or wall at 21a, the latter being provided with a recess through which the outer end of the bolt is projectable to the locking position of Figure 3.

Vertically reciprocable just inside the jamb 21a, and guided by screws 65 engaged in a vertical slot 66 therein, is an operator block 67 to which is rigidly secured a detent member 68. Block 67 is key-controlled in its reciprocation through the operator 69. At its lower end block 67 carries a pad 70 of insulating material adapted to engage the arm of a switch 71 to open the switch when the block descends. At its upper inner edge block 67 carries a finger 72 of insulating material adapted upon descent of the block to engage the arm of a switch 73 to open the switch. At its inner edge block 67 is provided with a notch 74 engageable by a latch 35a. Positioned in the path of movement of bolt 23a is a suitably guided plunger 75 carrying an insulating pad 76 adapted to engage the arm of a normally open switch 77 to close the latter. Switches 71 and 77 correspond respectively to switches 44 and 46 of the first embodiment and control the circuit to the buzzer 43a. Switch 73 corresponds to switch 46 of the first embodiment and controls the shorting circuit 43a and 59a. Coil 37a corresponds to coil 37 of the first embodiment and controls the latch 35a.

Upon closing door 22a, switch 18a will be closed, the lights will be controlled as before, and with the alarm circuit 16a intact, coil 37a will be energized and latch 35a will consequently

be withdrawn from notch 74, freeing block 67 which is still retained frictionally, in its upper position of Figure 4. With bolt 23a moved to the locking position of Figure 3, switch 77 is closed and a reminder is given by buzzer 43a that a further operation must be carried out. Accordingly the person closing the premises, through operator 69, lowers block 67 to the position of Figure 3 so that detent member 68 is engaged in notch 25a, Figure 3, to hold bolt 23a in locked position. Concomitantly, switches 78 and 79 are opened so that the buzzer and shorting circuits are broken.

It is believed that the sequence of operations necessary in opening the premises will be evident from the above.

It will be understood that the embodiments of the invention disclosed herein are merely illustrative, and that variations in the form and arrangement of parts are possible without departure from the invention as defined in the following claims. In referring, in the claims, to "disturbance of" a protective circuit, is meant the affecting of the circuit, in a manner appropriate to the particular circuit, to disturb its normal current condition so that it is conditioned to cause operation of the alarm signal means.

I claim:

1. In an alarm system for premises including an entrance door, said system comprising a protective circuit and alarm signal producing means automatically operated upon disturbance of said circuit, the combination of a switch operable from the exterior of the door by an authorized person, a circuit across the protective circuit for shorting the protective circuit so that disturbance of the latter will not affect the signal producing means, said switch being arranged to control said shorting circuit, and means rendering said switch inoperative to open the shorting circuit when the protective circuit is in disturbed condition.

2. In an alarm system for premises including an entrance door, said system comprising a protective circuit and alarm signal producing means automatically operated upon disturbance of said circuit, the combination of a switch operable from the exterior of the door by an authorized person, a circuit across the protective circuit for shorting the protective circuit so that disturbance of the latter will not affect the signal producing means, said switch being arranged to control said shorting circuit, means rendering said switch inoperative to open the shorting circuit when the protective circuit is in disturbed condition, said last-named means comprising a circuit controlled in dependence upon the condition of the protective circuit, electromagnetic means in said last-named circuit, and latch means controlled by said electromagnetic means.

3. In an alarm system for premises including an entrance door, said system comprising a protective circuit and alarm signal producing means automatically operated upon disturbance of said circuit, the combination of a lock for the door comprising a movable bolt, a movable detent member for holding the bolt in locked position or for releasing the bolt, a circuit across said protective circuit for shorting the protective circuit so that disturbance of the latter will not affect the signal producing means, and a switch in said shorting circuit operable concomitantly with said detent so that when said detent is in holding position said switch is open and when said detent is in releasing position, said switch is closed.

4. In an alarm system for premises including an entrance door, said system comprising a protective circuit and alarm signal producing means automatically operated upon disturbance of said circuit, the combination of a lock for the door comprising a movable bolt, a movable detent member for holding the bolt in locked position or for releasing the bolt, a circuit across said protective circuit for shorting the protective circuit so that disturbance of the latter will not affect the signal producing means, a switch in said shorting circuit operable concomitantly with said detent so that when said detent is in holding position said switch is open and when said detent is in releasing position, said switch is closed, and a latch member controlled from said protective circuit and effective to hold the detent against movement to holding position when said protective circuit is in disturbed condition.
5. In an alarm system for premises including an entrance door, said system comprising a protective circuit and alarm signal producing means automatically operated upon disturbance of said circuit, the combination of a lock for the door comprising a movable bolt, a movable detent member for holding the bolt in locked position or for releasing the bolt, a circuit across said protective circuit for shorting the protective circuit so that disturbance of the latter will not affect the signal producing means, a switch in said shorting circuit operable concomitantly with said detent so that when said detent is in holding position said switch is open and when said detent is in releasing position, said switch is closed, a latch member controlled from said protective circuit and effective to hold the detent against movement to holding position when said protective circuit is in disturbed condition, and means preventing holding effect of the latch member with respect to the detent member when the latter is in its holding position and the protective circuit is in disturbed condition.
6. In an alarm system for premises including an entrance door, said system comprising a protective circuit and alarm signal producing means automatically operated upon disturbance of said circuit, the combination of a lock for the door comprising a movable bolt having a notch therein, a detent member movable between positions wherein it engages in said notch to hold the bolt against unlocking movement and wherein it is free of the notch so as to release the bolt for unlocking movement, a key-actuated operator for said detent member, a circuit across said protective circuit for shorting the protective circuit so that disturbance of the latter will not affect the signal producing means, a switch in said shorting circuit, and control means for said switch including means operated by said operator so that the switch is open when the detent member is in holding position and is closed when the detent member is in releasing position.
7. In an alarm system for premises including an entrance door, said system comprising protective circuit and alarm signal producing means automatically operated upon disturbance of said circuit, the combination of a lock for the door comprising a movable bolt having a notch therein, a detent member movable between positions wherein it engages in said notch to hold the bolt against unlocking movement and wherein it is free of the notch so as to release the bolt for unlocking movement, a key-actuated operator for said detent member, said operator being

in the form of a pivoted disc operatively associated with the detent member through cam and follower means, a circuit across said protective circuit for shorting the protective circuit so that disturbances of the latter will not affect the signal producing means, a switch in said shorting circuit, and control means for said switch including means operated by said operator so that the switch is open when the detent member is in holding position and is closed when the detent member is in releasing position.

8. In an alarm system for premises including an entrance door, said system comprising a protective circuit and alarm signal producing means automatically operated upon disturbance of said circuit, the combination of a lock for the door comprising a movable bolt having a notch therein, a detent member movable between positions wherein it engages in said notch to hold the bolt against unlocking movement and wherein it is free of the notch so as to release the bolt for unlocking movement, a key-actuated operator for said detent member, said operator being in the form of a reciprocable block to which the detent member is secured, a circuit across said protective circuit for shorting the protective circuit so that disturbance of the latter will not affect the signal producing means, a switch in said shorting circuit, and control means for said switch including means operated by said operator so that the switch is open when the detent member is in holding position and is closed when the detent member is in releasing position.

9. In apparatus of the class described, a lock including a movable bolt, a movable detent member for holding the bolt in locked position or for releasing the bolt, a circuit having a signal device therein, a switch in said circuit controlled in dependence upon the movements of said detent member, said switch being closed when the detent member is in releasing position and open when the detent member is in holding position, and a second switch in said circuit controlled in dependence upon the movement of said bolt, said second switch being open when the bolt is

5
in unlocking position and closed when the bolt is in locking position, said circuit being completed so that a signal is given when said bolt is in locking position and said detent member is in releasing position.

10. In an alarm system for premises including an entrance door, said system comprising a protective circuit and alarm signal producing means automatically operated upon disturbance of said circuit, the combination of a lock for the door comprising a movable bolt, a movable detent member for holding the bolt in locked position or for releasing the bolt, a circuit across said protective circuit for shorting the protective circuit so that disturbance of the latter will not affect the signal producing means, a switch in said shorting circuit operable concomitantly with said detent so that when said detent is in holding position said switch is open and when said detent is in releasing position, said switch is closed, a local circuit having a signalling device therein, a switch in said local circuit controlled in dependence upon the movements of said detent member, said last-named switch being closed when the detent member is in releasing position and open when the detent member is in holding position, and a second switch in said local circuit controlled in dependence upon the movements of said bolt, said second switch being open when the bolt is in unlocking position and closed when the bolt is in locking position, said local circuit being completed so that a signal is given when said bolt is in locking position and said detent member is in releasing position.

11. A combination according to claim 6 wherein in the bolt in its unlocking position blocks movement of the detent member toward holding position.

12. A combination according to claim 3 wherein in the bolt and detent member have a fixed locational relation.

13. A combination according to claim 3 wherein in the bolt is mounted in the door and the detent member externally of the door.

JAMES C. HOWTON.
